(57) **CLAIM**

The ornamental design for an artificial fishing lure, as shown and described.

DESCRIPTION

FIG. 1 is a front-on view of my artificial fishing lure with the wings and tentacles clipped to show the head with more clarity;

FIG. 2 is left-side view of my artificial fishing lure;

FIG. 3 is a right-side view of my artificial fishing lure;

FIG. 4 is a left-side view of a non-distinct variation of the artificial fishing lure; and,

FIG. 5 is a right-side view of the non-distinct variation of the artificial fishing lure.

Subject matter shown in broken lines is environmental and forms no part of the claimed design.
